PERMUTATION LOCK

Elmer B. Stone, New Britain, Conn., assignor to
 The American Hardware Corporation, New
 Britain, Conn., a corporation of Connecticut

Application April 18, 1934, Serial No. 721,179

11 Claims. (Cl. 70—53)

My invention relates particularly to the type of permutation locks which are employed in connection with the doors of lockers and similar structures, and an object of my invention, among others, is to provide a lock of this type by means of which a dial of maximum size may be used upon a door of minimum size; and a further object of the invention is to provide a lock of this type which shall be simple in construction and particularly efficient in operation.

One form of a device embodying my invention and in the construction and use of which the objects herein set out, as well as others, may be attained is illustrated in the accompanying drawing in which—

Figure 1 is a face view of a portion of a set of lockers one of which is equipped with my improved lock.

Figure 2 is a side view of the same.

Figure 3 is a view on enlarged scale of a portion of a locker door equipped with my improved lock and with parts broken away to show construction.

Figure 4 is a view in section on a plane denoted by the dotted line 4—4 of Fig. 3.

Figure 5 is a view in section on a plane denoted by the dotted line 5—5 of Fig. 4.

Figure 6 is a view in section on a plane denoted by the dotted line 6—6 of Fig. 3 but on reduced scale and with parts broken away to show construction.

Figure 7 is a sectional view illustrating a way for changing the combination of the lock.

Figure 8 is a detail view looking into the rear of the lock case.

In the accompanying drawing the numeral 1 denotes the front plate of a set of lockers comprising openings with doors 8 closing such openings, one of such doors being shown in Fig. 1 as equipped with my improved lock. A handle 9 is slidably mounted upon the door for the purpose of latching and unlatching the fastening for the door, such fastening being controlled by my improved lock.

In prior structures, owing to the small space available on the front of the door, the use of a dial of small dimensions has been compelled, and as lockers are frequently located in dark places, the use of such a small dial is objectionable owing to the difficulty in seeing the numbers upon it. However, these lockers and the doors are of standard construction and therefore the lock case and its mechanism is located in a definite position with respect to the handle 9 and this has compelled the use of the smaller dial here-

inbefore referred to. By the use of my improved lock I am enabled, without changing the position of the lock case and its mechanism, to make use of a large dial, the only change required in the standard equipment being embodied in the dial structure, the lock case and its mechanism being undisturbed.

These prior structures embody a bolt case 10 commonly constructed by bending metal at the edge of the door 8, as best shown in Fig. 5, such 10 case extending from the top to the bottom of the door. A bolt 11 of tubular form is slidably mounted within the case 10, the handle 9 being secured at its upper and lower ends to the bolt by means of projections 12 which extend through slots in 15 the door for the purpose of permitting sliding movement of the handle.

A retainer 13 is attached to the bolt within the opening therein, the outturned end of the retainer projecting through a slot 14 in the wall 20 of the bolt in position for its end to engage the edge of a slot 15 in the case 10, thereby holding the bolt in its unlocked position. A catch 16 secured inside of the frame or front plate 7 projects in position to enter the slots 14 and 15, the 25 upper edge of the slot 14 engaging within a notch in the catch to retain the door in its locked position, and as shown in Fig. 6. The bolt is held in its locked position by a lock bolt pivotally mounted within a lock case 17 secured to the 30 rear face of the door 8 as by means of threaded studs and nuts, the nose 18 of said lock bolt extending through a slot in the side of the lock case and a slot 19 in the bolt 11, engagement in said slot locking the sliding bolt against movement.

Movement of the lock bolt is controlled by means of a key plug 20 of any ordinary type and adapted to receive a key in the key slot 21 as a means to release the key plug for rotating movement. The lock bolt is also controlled in its 40 movement by a set of tumblers rotatably mounted upon the key plug and heretofore operated in the usual manner by means of a dial mounted concentrically with said plug and through an opening in the center of which dial the key is 45 inserted into the key plug.

As hereinbefore explained the structure thus far described is of old and well-known form, the key within the key plug being made use of at any time to permit release of the nose on the 50 locking bolt from engagement with the sliding bolt. The dial and tumblers are separately operated for the same purpose independently of the key.

In effecting my purpose and in order to enable 55

the use of a large dial without changing the position of the key plug and the tumblers within the lock I pivotally mount my dial 22 upon a stud 23 projecting from a back plate 24 secured to the face of the door 8, as by means of threaded studs and nuts, and as shown in Fig. 4 of the drawing. A retaining ring 25 is fastened to the back plate in any suitable manner, said ring being undercut to receive a lip on the dial or on a part secured to the dial in a manner common to dial construction. A gear ring 26 is secured to the back of the dial in any suitable manner, in the structure herein shown this ring having the lip engaged by the ring 25, teeth 27 on the inner edge of the ring 26 meshing with teeth on a pinion 28 rotatably mounted upon the key plug 20. One of the tumblers 41 of a set of disk tumblers is rotated by the pinion 28, other tumblers not being shown, as they are of ordinary construction provided with interengaging lugs and also with notches, the latter of which are caused to register to enable the locking bolt to be "thrown." This arrangement will be readily understood by those skilled in the art and for this reason a further and detailed description is omitted herein.

A hole 29 is formed through the dial 22, through which hole access may be had to the key slot in the plug 20. It will be understood that the locking bolt may be released for action by the use of a key at any time, whenever the dial is rotated to uncover the key plug, this arrangement being well understood by those skilled in the art and embodying a detent 40 movably mounted to enter the notches in disk tumblers when said notches are aligned by operation of the dial 22, the tumbler 41 comprising one of the set of tumblers and which is attached to the pinion 28, being shown in Fig. 8 of the drawing. The detent 40 is pivotally mounted on the lock bolt hereinbefore mentioned and when in its locking position, that is, disengaged from the notches in the tumblers, said detent has a dog 42 presented in its path of movement thereby preventing movement of the locking bolt and disengagement of its nose 18 from the bolt 11. However the dog 42 is secured to a slide which is connected for operation by the key plug 20, so that when said plug is turned by use of a key the dog is moved thereby permitting disengaging movement of said nose.

In the particular construction herein shown a positioning disk 30, of a more or less springy nature, is located back of the dial 22 and in contact therewith, this disk being held against rotation in any suitable manner as by lugs extending into holes in the back plate 24, and as shown in Fig. 4 of the drawing, said disk being in contact with the pinion 28. This pinion is secured to a sleeve 31 which extends through the back plate and door and into the lock case, the outermost tumbler of the set of tumblers hereinbefore referred to being secured to the inner end of said sleeve.

It will be understood that the pinion 28 is so timed in its rotation with respect to the gear ring 26 that the proper number of rotations will be imparted to the tumblers in the movements of the dial to effect the final unlocking positions of the tumblers as the dial is rotated to bring its graduation marks successively into registry with the pointer 33.

It will be noted that the gear ring 26 meshing with the pinion 28 imparts a faster rate of rotation to said pinion and the tumblers connected therewith. These tumblers must be rotated one

or more complete rotations depending upon the number of tumblers employed and their positions relatively to the tumbler operating member as the pinion 28. In a permutation lock mechanism in common use three tumblers are employed and with these tumblers connected directly with the dial, the latter must be rotated in opposite directions a number of times, three complete rotations in one direction being required, two complete rotations in the opposite direction and one complete rotation in the same direction as the first movement.

With my improved mechanism these pluralities of rotations of the tumblers in opposite directions may be obtained by a partial rotation only of the dial, the latter requiring a very limited movement to effect a number of rotations of the pinion 28 and the tumblers connected therewith. This comprises an important feature of my invention.

To enable a change in the combination of the lock in a ready and accessible manner without disturbing the mechanism at the back I mount the dial 22 so that it may be moved outwardly on the stud 23 sufficiently to disengage the gear teeth 27 from the teeth of the pinion 28, and as shown in Fig. 7 of the drawing. To this end an undercut recess 35 is formed in the outer end of the knob 36 of the dial and a screw 37 extends inwardly from this recess and is threaded at its inner end into the stud 23. A retaining or locking screw 38 is threaded at its inner end into the end of the screw 37, extending lengthwise within the stud 23. The screws 37 and 38 being loosened sufficiently to permit said movement of the dial 22, the flange on the retaining ring 25 will engage the lip on the gear ring, thereby limiting the outward movement of the dial to the extent shown in Fig. 7. A collapsible disk 39 is fitted to the recess 35 and is forced thereinto to tightly engage the undercut edge of said recess, said disk being removed before the screws 37 and 38 are loosened.

When it is desired to change the combination of the lock the disk 39 is pried out by means of any suitable tool, the screw 37 is loosened to the extent shown in Fig. 7 and sufficiently to permit the teeth of the ring 26 to be disengaged from the teeth of the pinion 28. The dial may now be turned independently of the pinion to such extent, denoted by the graduations on the dial, as may be desired and the dial is then pushed in to re-engage the teeth of the ring 26 with the teeth of the pinion 28, the screw 37 is screwed into its former position and a new disk 39, which may be supplied for the purpose, is forced into the recess to secure the parts again molestation. When the dial is pulled outwardly the head of the screw 38 will prevent such dial from being disengaged from the stud 23.

I claim:

1. A permutation lock including a supporting member, a plurality of tumblers rotatably supported by said member, each of said tumblers requiring at least a complete rotation to register one with another for unlocking operation, a rotatably mounted dial, and a multiplying geared connection between said dial and tumblers to increase the rate of movement of the tumblers relatively to that of said dial to place each of said tumblers in unlocking position by less than a complete rotation of said dial.

2. A permutation lock including a supporting member, a plurality of tumblers rotatably supported by said member, a rotatably mounted dial,

- a gear ring secured to said dial and having teeth on its inner edge, and a geared connection between the teeth on said ring and said tumblers for rotation of the latter.
5. 3. A permutation lock including a rotatably mounted dial, a gear ring secured to said dial and having teeth on its inner edge, a supporting member having its axis located within the boundaries of said gear ring, a set of tumblers rotatably mounted on said supporting member, and a multiplying geared connection between said ring and tumblers and including a pinion located within the boundaries of said gear ring.
4. A permutation lock including a rotatably mounted dial having an opening between its axial center and its periphery, a gear ring secured to said dial and having teeth on its inner edge, a key plug having its axis within the boundaries of said gear ring and in position to be uncovered by said opening in the dial, locking mechanism operatively connected with said key plug, a set of tumblers rotatably supported by said key plug, and a geared connection between said ring and said tumblers and including a toothed driving member operatively connected with said tumblers.
5. In a permutation lock, a toothed member rotatably mounted to operate a set of tumblers, a gear engaged with said toothed member, a stud, a dial to which said gear is secured, said dial being rotatably mounted for sliding movement on said stud to permit disengaging movement of the teeth of said gear from the teeth of said member, and a screw extending into said stud to limit outward movement of said dial.
35. 6. In a permutation lock, a toothed member rotatably mounted to operate a set of tumblers, a gear engaged with said toothed member, a stud, a dial to which said gear is secured, said dial being rotatably mounted for sliding movement on said stud to permit disengaging movement of the teeth of said gear from the teeth of said member, and means to limit outward movement of said dial on said stud.
45. 7. In a permutation lock, a toothed member rotatably mounted to operate a set of tumblers, a gear engaged with said toothed member, a dial to which said gear is secured, said dial having a hub projecting therefrom with a recess in its end,
- a stud on which said dial is rotatably mounted, a screw projecting into said stud to limit outward movement of the dial, and a disk forced into said recess to cover the head of said screw.
8. In a permutation lock, a toothed member rotatably mounted to operate a set of tumblers, a gear engaged with said toothed member, a dial to which said gear is secured, a stud on which said dial is slidably and rotatably mounted, fastening means for retaining said dial against sliding movement on said stud, and means for covering said fastening means.
9. A lock including key operated mechanism with an opening for insertion of a key, tumblers to control movement of a member of said mechanism, and a rotatably mounted dial operatively connected with said tumblers to control operation thereof, said dial overlying said key opening which is located between the center and periphery of the dial and having a hole positioned to uncover said key opening for access thereto.
10. In combination with a lock adapted to be secured on a closure and having an opening for insertion of a key, said lock including a key plug accessible through an opening in said closure, tumblers rotatably mounted on said key plug, locking members operatively connected with said tumblers for operative control thereby, and a dial having its axis removed from the axis of said key plug and having a geared connection with said tumblers, said dial having an opening between its center and periphery for access of a key to said key plug.
11. In a permutation lock adapted for attachment to a door, a plurality of tumblers rotatably supported on the inside of said door, each of said tumblers requiring at least a complete rotation to register one with another for unlocking operation, a rotatably mounted dial located on the outside of said door, and a multiplying geared connection located on the outside of said door and connecting said dial and tumblers to increase the rate of movement of the tumblers relative to that of said dial to impart more than a complete rotation to each tumbler for placing each tumbler in an unlocking position by less than a complete rotation of the dial.

ELMER B. STONE.
